J. H. GRAYSON

WINDOW SCREEN

Filed Nov. 11, 1920

FIG. I.

FIG. 2.

FIG. 3.

INVENTOR

JAMES H. GRAYSON

BY

Hazard & Miller
ATTORNEYS.

UNITED STATES PATENT OFFICE.

JAMES H. GRAYSON, OF KANSAS CITY, MISSOURI.

WINDOW SCREEN.

Application filed November 11, 1920. Serial No. 423,280.

To all whom it may concern:

Be it known that I, JAMES H. GRAYSON, a citizen of the United States, residing at Kansas City, in the county of Jackson, State 5 of Missouri, have invented new and useful Improvements in Window Screens, of which the following is a specification.

This invention is a window screen adapted to be positioned between the upper and lower 10 sashes of a window and so arranged as to be moved by one of the sashes into position to close the opening left by said sash when the latter is opened.

The invention will be readily understood 15 from the following description of the accompanying drawings in which;

Figure 1 is a front elevation of a window having the improved screen applied thereto.

Fig. 2 is an enlarged vertical section partly 20 broken away and taken on the line 2—2 of Fig. 1.

Fig. 3 is an enlarged front elevation of a corner of the window partly broken away.

In the drawings a usual window frame is 25 shown at 1, having the usual upper and lower sash 2 and 3 slidable therein in well known manner. A space 4 is left between the adjacent surfaces of the upper and lower sashes in which the improved window screen 30 is mounted. For this purpose a guide way 5, preferably, formed of metal is provided in the space 4, said guide way extending across the top of the window frame and down the sides thereof. A groove 6 is provided in this guide way in which the edges 35 of the window screen are received to provide a guide way for the screen and a tight joint between the window frame and the screen. The screen is shown as formed of 40 a usual mesh 7, the edges of which are reinforced to form the frame of the screen as by a metallic strip bent over the edges of the mesh and abutting against the opposite surface of the mesh as shown at 8 and 9.

The screen is normally held in its guide way at the upper end of the window frame and is preferably of such length as to end at the top of the lower sash when it is in this position, as clearly shown in Fig. 1. 45 When the lower sash of the window is raised the screen is adapted to be lowered so as to close the opening left by the lower sash. For this purpose flexible connections running over pulleys at the upper end of the window frame are connected at their respective ends to the screen and to the lower

sash, so arranged that when the lower sash is closed the screen will be supported by said flexible connections at the upper end of the window frame and when the lower 60 sash is raised the screen will be moved by gravity downwardly in its guide way to close the opening left by the lower sash.

The flexible connections are shown as tapes 10 having hooked ends 11 received in the frame plate 9 of the screen. These tapes pass over pulleys shown as comprising rollers 12 journaled upon pins 13 having offset ends 14 adapted to be received within the guide way 5 for supporting said pins. The 70 guide way is, preferably, a hollow construction, and is cut away as shown at 15 above said pins to permit of the ready insertion of the ends of said pins within the hollow guide way. The opposite ends of the tapes 10 are removably connected to the lower sash of the window as by providing hooks 16 upon the top of the lower sash, these hooks being arranged to receive eyes 17 at the ends of the tapes 10. 80

When it is desired to lower the screen without raising the lower sash of the window it is only necessary to unhook the tapes from the lower sash and the screen will then drop to a position in the lower portion 85 of the window frame. Usually, however, the tapes 10 will be connected to the lower sash so that the movement of the screen will be controlled by the movement of the lower sash as previously described. 90

It will be obvious that various changes may be made in the construction as thus described without departing from the spirit of the invention.

What is claimed is:

1. A window screen comprising an inverted U-shaped frame that is adapted to be positioned in a window frame between the sashes therein, said inverted U-shaped frame being formed of tubular material on 100 the inner face of which is formed a continuous channel, a screen carrying frame arranged for sliding movement in said channel, flexible members secured to the upper rail of said screen carrying frame, and flexible member supporting rollers journaled on 105 the upper portion of the tubular frame.

2. A window screen comprising an inverted U-shaped frame formed of sheet metal and adapted to be positioned in a 110 window frame between the sash therein, the legs of said U-shaped frame being of a

- length equaling the height of the window opening whereby to serve as parting strips between the sash, the inner faces of the vertical and horizontal portions of said inverted **5** U-shaped frame having channels formed therein, and a screen carrying frame arranged for sliding movement in said channels.
3. A window screen comprising an inverted **10** U-shaped frame formed of sheet metal and adapted to be positioned in a window frame between the sash therein, the inner faces of the vertical and horizontal portions of said inverted U-shaped frame having channels formed therein, a screen carrying frame arranged for sliding movement in said channels, rollers journaled on the horizontal rail of said inverted **15** U-shaped frame and flexible members secured to the

upper portion of the screen frame and ex- **20** tending over said rollers.

4. A window screen comprising an inverted U-shaped rigid frame adapted to be positioned in a window frame between the **25** sashes therein, a screen carrying frame ar-
ranged for sliding movement in the first frame, and flexible connecting means slid-
ingly associated with the first frame and con-
nected to the second frame, said flexible **30** means being adapted for connection with the lower sash of a window whereby the screen carrying frame will be lowered or elevated according as the sash is raised or lowered.

In testimony whereof I have signed my **35** name to this specification.

JAS. H. GRAYSON.
